(57) CLAIM

The ornamental design for a portion of a sanitary article, as shown and described.

DESCRIPTION

FIG. 1 is a perspective view of a portion of a sanitary article according to my new design.

FIG. 2 is a top plan view thereof.

FIG. 3 is a right side perspective view thereof, the left side perspective view being a mirror image of FIG. 3.

FIG. 4 is a right side view thereof, in an outstretched position, the left side view being a mirror image of FIG. 4; and,

FIG. 5 is a rear view thereof, in an outstretched position, the front view being a mirror image of FIG. 5.

The broken line showing in FIGS. 1-5 is for illustrative purposes only and forms no part of the claimed design.

1 Claim, 4 Drawing Sheets
